UNITED STATES PATENT OFFICE.

ALEXANDER M. MOYLAN, OF CENTURY, FLORIDA.

CAR-DOOR.

1,287,730.

Specification of Letters Patent. Patented Dec. 17, 1918.

Application filed December 10, 1917. Serial No. 206,499.

To all whom it may concern:

Be it known that I, ALEXANDER M. MOYLAN, a citizen of the United States, residing at Century, in the county of Escambia and 5 State of Florida, have invented certain new and useful Improvements in Car-Doors, of which the following is a specification.

This invention relates to an improved door construction and while adapted for general 10 application is more particularly designed for use as a box car door, the invention having as its primary object to provide an arrangement whereby the door will be supported for free and easy movement to open or 15 closed position.

The invention has as a further object to provide an improved supporting frame for the door as well as an improved type of roller bearing therefor.

20 And the invention has as a still further object to provide an improved type of hanger for supporting the door upon its roller bearings.

Other and incidental objects will appear 25 as the description proceeds, and in the drawings wherein I have illustrated the preferred embodiment of the invention, and wherein similar reference characters designate corresponding parts throughout the 30 several views:

Figure 1 is a front elevation showing my improved door applied to the side wall of a car and showing the door closed.

Fig. 2 is a vertical sectional view taken on 35 the line 2—2 of Fig. 1 and looking in the direction of the arrows, this view particularly showing the mounting of the roller bearings employed within the upper and lower supporting bars of the door frame.

40 Fig. 3 is a fragmentary sectional view taken on the line 3—3 of Fig. 1, showing the manner in which the outer margin of the door is adapted to enter the front supporting bar of the frame when the door is closed 45 as well as illustrating the latch for the door.

Fig. 4 is a fragmentary perspective view particularly showing one of the elbows of the door frame.

50 Fig. 5 is a plan view particularly illustrating the construction of the hangers for the door as well as the manner in which the said

hangers are adapted to engage the roller bearings employed.

Fig. 6 is a longitudinal sectional view 55 more particularly illustrating the construction of the body of the door.

Fig. 7 is a view similar to Fig. 6, and showing a modified form of the invention.

Fig. 8 is a detail perspective view showing the end sections of the modified form of 60 door and the screen between the said sections.

Fig. 9 is a fragmentary sectional view 65 showing the manner in which the hangers of the middle section of the modified form of door are offset to support the said sections in front of the end sections of the door, and

Fig. 10 is a detail perspective view showing one of the offset hangers of the middle 70 section of the door, as employed in the modified structure.

Referring more particularly to the drawings, I have shown my improved door in connection with one side wall 10 of a box 75 car. Formed through this wall is the door opening 11. In carrying out the invention I employ a substantially rectangular door frame including upper and lower parallel supporting bars 12 and 13, a forward stop 80 bar 14 and a rear stop bar 15 extending parallel to the forward stop bar. As particularly shown in Fig. 2, the bar 12 is arranged immediately above the upper edge of the door opening to lie flush therewith while 85 the bar 13 is disposed slightly below the lower edge of the door opening. Further, it will be observed upon reference to Fig. 3, that the front stop bar 14 is mounted flush with the forward edge of the door opening. 90 Connecting the several bars at the corners of the frame are elbows 16, one of which is shown in detail in Fig. 4 of the drawings. These elbows telescopically receive the said bars and the angularly disposed portions of 95 the elbows are provided with lateral lugs or ears 17 through which suitable fastening devices are fitted for rigidly connecting the frame with the side wall of the car. The several bars of the frame are preferably formed of lengths of metallic pipe and with the exception of the bar 15 are longitudi-

100

nally slotted upon the inner sides thereof. The elbows 16 are also formed upon their inner sides with similar slots. Fitted through said elbows to engage in suitable notches 18 in the ends of the top and bottom bars 12 and 13 of the frame are bolts or other fastening devices 19. Similar fastening devices 20 are fitted through the said elbows to engage in notches similar to the notches 18 in the ends of the end bars 14 and 15 of the frame. The fastening devices 19 and 20 are extended into the side wall 10 of the car to coöperate with the fastening devices engaging the ears 17 of the said elbows for connecting the frame with the said wall. As will thus be seen, the fastening devices 19 and 20 will act to lock the top and bottom bars of the frame as well as the end bars thereof against rotation upon the said elbows. The slots of the several bars 12, 13 and 14 will consequently be rigidly held to register with the slots of the elbows.

Mounted to move within the door frame is a door indicated as a whole by the reference numeral 21. This door is preferably constructed of metal, and as shown in Fig. 6 of the drawings, is formed of a plurality of spaced parallel sections extending vertically between the top and bottom bars of the frame and rigidly connected by batten strips 22. The upper and lower edges of these sections as well as of the strips 22, preferably terminate flush with the inner faces of the said bars. Formed on the ends of the door sections, medially thereof, are longitudinally extending hangers 23 and while I have shown each of the sections as provided with a pair of hangers, still, it will be understood that the number of hangers employed may be varied as desired. These hangers are preferably formed integral with the door sections and, as shown in Fig. 2, are of equal thickness therewith to extend through the slots in the top and bottom bars of the frame. Formed on the shanks of the said hangers are oppositely extending lateral bearing brackets 24. These bearing brackets are substantially L-shaped and, as shown in detail in Fig. 5 of the drawings, are presented downwardly to confront the hanger shanks at opposite sides thereof.

Mounted within the upper and lower supporting bars 12 and 13 of the frame to coöperate with the hangers of the door, are spherical roller bearings 25. These bearings, as particularly shown in Fig. 2 of the drawings, are loosely received within the said bars to travel longitudinally therein and are each provided with a circumferential groove 26 defining a reduced annular bearing pin 27 axially of the bearing. A pair of the roller bearings 25 is employed in connection with each of the hangers 23 and are arranged at opposite sides of the

hanger shanks to freely receive the brackets 24 within the slots 26 of the said bearings to engage over the bearing pins 27. The brackets 24 of the hangers will thus coat with the bearing pins 27 of the roller bearings to support the door for movement longitudinally of the door frame upon the said bearings, the bearings, of course, being caused to rotate within the bars 12 and 13 of the frame as the door is shifted so that the door may be freely and easily opened or closed. Furthermore, it will be noted that this construction provides an arrangement whereby the possibility of binding of the door between the upper and lower bars of the frame will be eliminated while the door will be rigidly supported against lateral play. When moved to open position the inner margin of the door will abut the inner stop bar 15 while, when the door is closed, the outer margin of the said door will, as shown in Figs. 3 and 6 of the drawings, be received within the slot in the forward stop bar 14. Swingly connected with this bar is a latch 28 mounted upon a bolt or other suitable fastening device 29 extending through the bar and adapted to engage through a staple 30 upon the door for holding the door closed. At its free end the latch 28 is, as shown in Fig. 1, preferably formed to receive a suitable seal. Mounted upon the side wall of the car at the inner vertical edge of the door opening, is a stop 31 arranged to coöperate with an inwardly directed flange 32 upon the inner edge of the door for limiting the door in its movement to closed position and providing a closed joint between the door and the said wall of the car at the inner margin of the door. In order that the lower supporting bar 13 of the frame may be effectively drained, this bar is, as particularly shown in Figs. 2 and 6 of the drawings, provided with a plurality of spaced drain openings.

In Figs. 7, 8, 9 and 10 of the drawings I have illustrated a modified form of the invention which relates more particularly to the mounting of the sections of the door. In this modification the side wall of the car has been indicated at 33 and is shown as formed with a door opening 34. Surrounding this opening, is the door frame 35 identical with the frame of the preferred construction. The door is formed of a plurality of sections including end sections 36 and middle sections 37. All of these sections are generally similar to the sections of the door previously described, the sections 36 being provided at their ends with hangers 38 identical with the hangers 23 of the preferred construction and arranged to coöperate with similar roller bearings within the upper and lower supporting bars of the frame to suspend the door for movement

longitudinally within the frame. Formed at the inner edge of the innermost section 36 of the door is a lateral flange 40 to coöperate with a stop 41 upon the wall of the car 5 for limiting the door in its movement to closed position, this stop and flange being similar to the corresponding elements of the preferred construction. In carrying out the modification the door sections 36 are formed 10 at their inner edges with outwardly extending lateral flanges 42 between which are arranged a plurality of rods 43 rigidly connecting the said sections and supporting the sections in spaced parallel relation. Overlying these rods is a screen 44. As shown in detail in Fig. 10 of the drawings, the middle sections 37 of the door are formed with hangers 45 the shanks of which are offset to support the said middle sections in front 15 of the end sections 36 lying against the outer edges of the flanges 42 of the said end section. The hangers 45 are otherwise constructed in accordance with the hangers of the preferred form of the invention and co- 20 operate with roller bearings 39 similar to the bearings 25 of the preferred construction. The sections 37 are formed to overlap at their inner edges closing the space between the sections 36 of the door and at 25 their outer edges are provided with inwardly turned flanges 46 to coöperate with the flanges 42 of the sections 36 for limiting the movement of said middle sections to closed position. One of the sections 37 is 30 equipped with an approved latch 47 while the other section is equipped with a staple 48 for receiving the latch so that the said sections may be sealed.

40 This modified form of the invention provides an arrangement whereby the middle sections 37 of the door may be arranged to expose the screen 44 and ventilate the car through the door opening 34. At the same time this result is accomplished without displacing the door. Mounted upon the end sections 36 of the door adjacent their outer edges, are stop pins 49 adapted for engagement with the outer edges of the middle sections 37 for limiting these latter sections in 45 their movement to open position. For holding the said sections 37 in such position these sections are equipped with latches 50 to engage over the said stop pins. Shifting of the middle sections of the door when open, due to movement of the car, will thus be 50 prevented.

55 Having thus described the invention, what is claimed as new is:

60 1. A device of the character described including a tubular supporting bar, a spherical bearing loosely fitted therein to travel within the bar and formed with a bearing pin, a door, and a hanger extending from

the door into the bar and including a hanger 65 shank having a lateral L-shaped bracket extending therefrom and engaging over said pin for supporting the door upon the bearing.

2. A device of the character described including a tubular supporting bar, spherical bearings loosely fitted therein to travel within the bar and formed with bearing pins, a door, and a hanger extending from the door and including a hanger shank projecting into the bar between said bearings and formed with oppositely directed lateral L-shaped brackets engaging over the bearing pins for connecting said bearings and supporting the door upon the bearings. 70

75 3. A device of the character described including upper and lower parallel tubular supporting bars, upper and lower pairs of spherical bearings mounted to travel within the bars respectively and formed with bearing pins, a door, a hanger projecting from the upper margin of the door and including a hanger shank projecting into the upper bar between the bearing pins of the upper 80 air of bearings and formed at its outer 85 terminal with oppositely directed lateral L-shaped brackets engaging over the said pins and connecting the bearings of said pair, and a hanger projecting from the lower margin of the door and including a hanger shank projecting into the lowermost bar between the bearing pins of the lower 90 pair of bearings and formed in spaced relation to its lower terminal with oppositely 95 directed lateral L-shaped brackets engaging over the bearing pins of the lower pair of 100 bearings and connecting the bearings of such latter pair.

4. A device of the character described including a door frame having parallel tubular top and bottom bars, parallel tubular forward and rear end bars, and elbows connecting said bars and formed with slots, the top and bottom bars and the forward end bar being longitudinally slotted, means extending through the said elbows and engaging the ends of said bars for holding the slots thereof in register with the slots of the elbows, lugs formed on the elbows, fastening devices engaging through said lugs for securing the frame in operative position, the said means being extended beyond the elbows to coöperate with the said fastening devices for also securing the frame in position, and a door mounted within the door frame and operatively received through 110 said slots. 115

5. A device of the character described including a tubular supporting bar, a pair of spherical bearings loosely fitted therein to travel within the bar and formed with bearing pins, a door, and a hanger extending from the door into the bar and including 120 125

a hanger shank projecting between the bearings and coacting with said pins for spacing the bearings apart, and brackets carried by the shank and engaging over the bearing pins for connecting the bearings and supporting the door therefrom.

6. A device of the character described including a tubular supporting bar, a pair of spherical bearings loosely fitted therein to 10 travel within the bar and formed with bear-

ing pins, a door, and a hanger projecting from the door into the bar between said bearings and engaged with the bearing pins for connecting the bearings and supporting the door therefrom, the hanger being 15 adapted for free disengagement from the bearings.

In testimony whereof I affix my signature.

ALEXANDER M. MOYLAN. [L. S.]
